(57) **CLAIM**

We claim the ornamental design for an input and output buffer module for clinical analyzer, as shown and described.

DESCRIPTION

FIG. 1 is a front, top and right side perspective view of an input and output buffer module for clinical analyzer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawing views are included for the purpose of illustrating portions of the input and output buffer module for clinical analyzer that form no part of the claimed design.
